(57) **CLAIM**

The ornamental design for an energizing coil for driving a motor driven valve, as shown and described.

DESCRIPTION

FIG. 1 is a right-front perspective view of an energizing coil for driving a motor driven valve showing my new design;

FIG. 2 is a right-rear perspective view thereof;

FIG. 3 is a front, elevation view thereof;

FIG. 4 is a rear, elevation view thereof;

FIG. 5 is a top, plan view thereof;

FIG. 6 is a bottom view thereof;

FIG. 7 is a right-side, elevation view thereof; and,

FIG. 8 is a left-side, elevation view thereof.

The broken lines in the drawings illustrate environmental structure and form no part of the claimed design.
